UNITED STATES PATENT OFFICE.

HENRY H. WAIT, OF CHICAGO, ILLINOIS, ASSIGNOR TO INTERNATIONAL SEPARATOR COMPANY, OF CHICAGO, ILLINOIS, A CORPORATION OF NEW JERSEY.

MAGNETIC ORE-SEPARATOR.

No. 832,828.

Specification of Letters Patent.

Patented Oct. 9, 1906.

Application filed March 20, 1905. Serial No. 261,077.

To all whom it may concern:

Be it known that I, HENRY H. WAIT, a citizen of the United States, residing at Chicago, in the county of Cook and State of Illinois, have invented a certain new and useful Improvement in Magnetic Ore-Separators, of which the following is a full, clear, concise, and exact description.

My invention relates to a magnetic separator; and its object is to provide an improved construction of the parts adjacent to the separating-gap such that an effective separation and division of the magnetic material from that which is non-magnetic can be accomplished with the minimum expenditure of energy and with the least possible liability of either the magnetic or non-magnetic product containing any considerable percentage of the other. In other words, the object is

to obtain as clean a concentrate as possible.

My invention relates generally to that type of magnetic separator in which the material to be treated is passed between the surface of a revolving drum or armature and a magnet-pole facing the same; and the invention resides particularly in the shaping of the pole-piece with reference to the armature, the location of the divider-plate, and the provision of a non-magnetic screen for the pole-piece so shaped and placed with reference to the divider-plate and pole-piece as to produce the most effective separation of the magnetic and non-magnetic particles.

I will describe my invention particularly by reference to the accompanying drawings, which illustrate the preferred embodiment thereof, and the parts, improvements, or combinations which I regard as novel will be pointed out in the appended claims.

Figure 1 is a view in elevation and half in section of an ore-separator constructed in accordance with my invention. Fig. 2 is a detail view showing the manner in which the surface of the armature is built up. Fig. 3 is a sectional detail, on an enlarged scale, illustrating the parts at the working gap of the machine, showing approximate directions of the lines of force. Fig. 4 is a similar sectional detail showing the paths taken by the different kinds of ore particles at the place of separation.

In the magnetic attraction of a particle, the movement is always in the direction of an increase in density of the magnetic flux—that is

to say, the movement is toward the densest portion of the field or along converging lines of force. In general the attraction is along the lines of force, although there are certain cases where it may be at varying angles with the lines of force. Magnetic ore-separators have been constructed to utilize this principle by providing permeable projections or magnetic teeth upon the surface of a revolving armature and passing the material to be separated between these projections and a magnetic pole-piece, the idea being that the more magnetically-permeable particles in the mixture will be drawn along converging lines of force to the teeth or projections on the armature rather than to the surface of the pole-piece.

In Fig. 1 an ore-separator working on this plan is illustrated. The armature *c* is mounted to rotate between opposing pole-pieces *N* and *S*. A receiving-hopper *f* is provided from which the material is fed through the spout *g* and through suitable feed-controlling mechanism to the upper surface of the rotating armature, said material being carried around in the rotation of said armature past the pole-piece *N*, at which separation takes place. A divider *p* is provided underneath the armature with its edge extending up toward the working air-gap, and the magnetic material attracted to the surface of the armature is carried past the edge of the divider and falls on one side thereof, separation thus being effected.

In the machine illustrated the armature is composed of laminated plates *d d*, assembled upon the shaft *b*, and the plates are provided with teeth or serrations *e e* at their peripheries, the plates being assembled in relative positions to present the teeth in staggered rows upon the surface of the armature. Magnetizing-coils *m m'* are provided upon the opposing pole-pieces *N S* of the field-magnet to establish a magnetic flux between said pole-pieces and the armature—that is to say, across the air-gaps. The flux through one of these air-gaps is utilized for the purpose of separation, while the other pole-piece on the opposite side of the armature is for the purpose of balancing the magnetic pull, so that the armature may turn in its bearings with the least possible amount of friction.

In the machine illustrated the divider *p* is shown mounted upon a rocking shaft *p'*,

which may be adjusted by the mechanism shown to vary the position of the edge of the divider-plate according to the strength of the field and the material being treated.

Coming now to a particular description of the novel features of this invention, and referring first to Fig. 1, it will be seen that a shield *a* is provided over the face of the magnet-pole *N*, this shield being curved upwardly toward the surface of the armature instead of being concentric therewith. The pole-piece is cut away at the top, as shown in Fig. 1, so as to produce a concentration of the field just below the horizontal axis of the armature. The shield *a* is close to the armature at the top, but gradually curves away from it toward the lower edge of the pole-face, so as to allow a gradually-increasing space between said armature and said shield. By reference to Fig. 3 it will be seen that the magnetic lines of force diverge from the teeth of the armature toward the pole-piece *N*, and the shield-plate in front of the pole-face prevents the ore particles from coming into any position in which the lines of force will converge toward the pole-piece *N* instead of toward the armature. It will be seen that the shield *a* is close against the face of the magnet-pole at the lower edge, but gradually curves upward away from the pole-face and toward the armature, so that ore particles near the top are held by the shield much closer to the surface of the armature than they could get to the surface of the pole-piece. In other words, the shield is so located that the density of the magnetic flux at all places in the working gap will increase toward the teeth on the armature rather than toward the pole-face. The gradual increase in the width of the working gap between the armature-surface and the shield *a* permits the sheet of ore to gradually fan out in passing through the intense portion of the field. In other words, the opening of the working gap is constricted near the top to take only a certain quantity of material; but toward the denser portion of the field the space is increased to permit the magnetic particles to separate out more readily from the non-magnetic material.

Fig. 4 shows more clearly the arrangement and curvature of the pole-piece and the shield-plate and the location of the divider-plate with reference to the other parts. The pole-piece is arranged to produce the most intense magnetic action of the ore particles near the lower edge. The location of the divider-plate is determined as follows: Non-magnetic particles passing over the armature will fall outside of a line *X* tangent to the toothed surface of the armature, and the divider-plate will therefore be located somewhere inside of this line *X*. There must be room for attracted material adhering to the surface of the armature to pass beyond the edge of the

divider-plate. Assuming the largest-size particle to be treated, the curved line *K* is illustrated to bound the space which would necessarily be required by such a particle if it were held tightly against the surface of the 70 armature; but in many cases the magnetic particle which has been attracted to the armature will be released as soon as it leaves the densest portion of the field near the lower edge of the working gap. Disregarding the 75 effect of gravity, therefore, the attracted particle released from the surface of the armature at the point where the magnetic action begins to decrease will follow at least a path tangent to the armature, so that the edge of 80 the divider-plate must be outside of this line, (indicated by the line *Z*.) The actual trajectory of the falling magnetic particle, however, will be slightly more vertical, due to the 85 action of gravity, and the path of the outer edge of such a magnetic particle of maximum size released from the armature at the point where the magnetic field first begins to decrease in strength will be indicated by the line *Y*. The lines *X* and *Y*, therefore, form the inner 90 and outer limits of the space within which the divider-plate should properly be placed, and if there were no interference between the moving particles the edge of the divider-plate might be located close up in the angle 95 of these lines *Y* and *X*. As it is usually desirable to feed a considerable volume of ore into the separator, the interference between the particles fans out the stream of ore, so that the divider-plate cannot in practice 100 come quite up to the limits referred to, but will be located slightly inside of these limits, as shown in Fig. 4.

The shield-plate *a* should be so curved that non-magnetic particles thrown off the armature by centrifugal force against said shield and rebounding therefrom will always fall outside of the divider-plate and not be mingled with the magnetic material. In Fig. 4 a curvature of the shield-plate *a* is illustrated, 105 such that particles falling off tangentially from the armature at any point above the horizontal axis and striking the shield-plate will be given such an angle of rebound or deflection that they will always fall outside of 110 the divider-plate. This curvature is determined by the location of the divider-plate and the tangential trajectories of particles thrown off from the armature-surface, the 115 surface of the shield-plate being such as to form equal angles of incidence and deflection with the tangential lines of trajectory *T* and the lines *L* from a point outside of the edge of the divider-plate to the point where the particles strike the shield-plate. Preferably the 120 shield-plate *a* is made of non-magnetic material, such as brass; but it is possible to secure practically the same effect by using a plate of thin sheet-iron, because it becomes saturated 125 with only a very small portion of the total 130

flux, and therefore does not exert a very considerable influence on the directions of the lines of force.

I claim—

- 5 1. In a magnetic separator, the combination with a rotating carrier having permeable projections for causing divergences of the magnetic flux from its periphery, of a magnet pole-piece facing said carrier, said pole-piece projecting close to the surface of said carrier below the horizontal axis thereof and being cut away above said horizontal axis to concentrate the magnetic field between the pole-piece and carrier along a short arc just below the horizontal axis, a shield over the face of the pole-piece, said shield being curved upwardly away from said pole-face, and means for passing material to be separated between said carrier and said shield, said shield being located and shaped to provide a working gap in which the density of the magnetic flux shall increase toward the permeable projections on the carrier, whereby the magnetic particles are prevented from being drawn toward the pole-piece, and a divider-plate extending to the most concentrated portion of the field.
- 10 2. In a magnetic separator, the combination with a rotating armature having means for causing divergences of the magnetic flux from its periphery, of a magnet pole-piece facing said armature and projecting close to the periphery thereof along a short arc below the horizontal axis of said armature, the lower portion of the pole-piece approaching closer to the armature than the upper portion thereof, a shield over the face of the pole-piece, means for passing material to be separated through the working gap between said shield and said armature, said shield being curved gradually away from the pole-piece and toward the surface of the armature at the top to form a restricted opening through which the ore may be passed, the working passage between said shield and said armature being gradually increased in width toward its lower end, substantially as and for the purpose set forth.
- 15 3. In a magnetic separator, the combination with a rotating cylindrical armature having magnetic teeth at its periphery, of a pole-piece facing said armature, a non-magnetic shield over the face of said pole-piece, said shield being gradually curved away from said

pole upwardly toward the surface of said armature, thereby forming a working gap between said shield and armature of gradually-increasing width toward the lower end, the space between said shield and pole-piece being of gradually-decreasing width toward the same end; whereby a working gap is formed in which the density of the magnetic flux at all places therein will increase toward the teeth on the armature and not away from the pole-face.

4. In a magnetic separator, the combination with a horizontal rotating cylindrical armature having means for causing dispersions of the magnetic flux at its periphery, of a magnet pole-piece facing said armature and closely approaching thereto along an arc just below the plane of the horizontal axis thereof, the lower portion of said pole-piece approaching the armature more closely than the upper portion thereof, a thin shield for said pole-piece extending upwardly around the armature-surface, said shield being curved away from said pole-piece and gradually approaching the armature toward the top to form a working gap between said armature and said shield gradually increasing in width downwardly, and a divider-plate on the under side of said armature, said shield being given a curvature adapted to reflect particles thrown against said shield by said armature at such an angle that said particles will fall outside of the divider-plate; whereby non-magnetic material is prevented from rebounding into the magnetic concentrate.

5. In a magnetic separator, the combination with a horizontal revolving cylindrical armature having means for causing dispersions of the magnetic flux at its periphery, of a magnet-pole facing one side of said armature, a shield over the face of said pole-piece, said shield being curved gradually away from said pole upwardly toward the surface of said armature, and a divider-plate extending to the most concentrated portion of the field, said shield being given a curvature at its lower end adapted to deflect impinging particles outside of said divider-plate.

In witness whereof I hereunto subscribe my name this 13th day of March, A. D. 1905.
